UNITED STATES PATENT OFFICE.

JOHN MARCHBANK, OF LANSINGBURG, NEW YORK.

IMPROVEMENT IN PRINTING FLOOR-CLOTHS, &c.

Specification forming part of Letters Patent No. 37,298, dated January 6, 1863.

To all whom it may concern:

Be it known that I, JOHN MARCHBANK, of Lansingburg, in the county of Rensselaer and State of New York, have invented a new and useful Improvement in Printing Floor-Cloths; and I do hereby declare that the following is a full, clear, and exact description of the same, reference being had to the accompanying drawings, making a part of this specification, in which—

Figure 1 is a longitudinal vertical section of the apparatus used in practicing my invention, *x x*, Fig. 2, indicating the line of section. Fig. 2 is a plan or top view of the same. Fig. 3 is a face view of one of the blocks used in printing the cloth. Fig. 4 is a side view of the same. Fig. 5 is a face view of a pad or cushion which may be used in the printing process. Fig. 6 is a view of an indicator by which the different colors are properly distributed for use. Fig. 7 is a view of a design to be printed on the cloth; Fig. 8, views showing the different impressions given in order to print the design.

Similar letters of reference indicate corresponding parts in the several figures.

In printing oil or floor cloths it has hitherto been the practice to employ a separate block for each color, and those designs or patterns in which a great number of colors are employed involve a great deal of labor and time in the printing of them, as separate blocks are not only employed, but separate pads or cushions also for each color, in order that each block may be properly charged with the color designed for it. The printing, therefore, of elaborate designs by the old process is very slow and tedious. The proper registering of the blocks requires care and close attention, and the expeditious manipulation of them can only be acquired by time and practice. The cutting of the blocks is also an expensive feature, as each block is so cut as to form in relief the portion of the design which contains the color it is to print.

The within-described invention is designed to reduce the number of blocks to four for the printing of any design of any required number of colors, and to dispense entirely with the cutting of the blocks in relief to print the several colors separately.

To enable those skilled in the art to fully understand and construct my invention, I will proceed to describe it.

In order to render my invention as clear as possible, I will first describe the way in which I prepare the four blocks for the printing of the different colors.

The blocks *A* (see Figs. 3 and 4) may be of the ordinary size, and they are grooved or sawed at their face sides, as usual, so as to leave projecting pins by which the color is deposited upon the cloth. These pins, however, are not used as they are first formed by the saw. Every alternate line of pins from two adjoining sides of the blocks are removed. This will be fully understood by referring to Fig. 3. By supposing the dotted lines to be pins, a correct representation of an old block is obtained, and by supposing said dotted lines to be removed a representation of one of my blocks is given. The old blocks, as previously stated in the recital of invention, are cut away at their face sides, with the exception of the parts designed to receive the color to be printed by the block, one color only being printed by each block. In my invention a plurality of colors, if necessary, are printed from each block, and to effect this the several pins (designated by *a*) are charged with different colors, which are arranged in accordance with the design or pattern to be printed. This charging of the pins of the blocks with their appropriate colors is an important feature of the invention, and is accomplished as follows: I construct a box, *B*, (see Figs. 1 and 2,) containing a number of cells, *b*, the aggregate number of which is equal to the combined number of pins of the four blocks *A*; or the cells may be described as being equal to the number of pins of four blocks and disposed in such a way as to correspond to them in position when the blocks are placed side by side. (See Fig. 2.) The box *B* is divided into four parts or divisions, (indicated by Figs. 1, 2, 3, and 4,) each of which contains a number of cells equal to the number of pins on a block, and the several pins of a block are charged with their color by dipping the pins in the cells of the portion of the box *B* designed for it. In order to set this forth more clearly, I will describe the manner in which the cells *b* are supplied with their

respective colors, for it will be understood that the pins *a* of each block are charged with different colors, *C*.

Fig. 7 represents a design to be printed which contains four different colors, dark drab, light drab, ruby, and orange. I take a piece of paper or stiff pasteboard, *D*, Fig. 6, and perforate it with holes corresponding in number and position with the number of pins *a* on a block. This piece of paper I place on or over the design *c*, so that its upper left-hand hole will be over the upper left-hand square, *x*, of the second row of the design. In this position the perforated paper *D* will expose all the squares marked 1 in the design, and the squares thus exposed indicate the different places of the colors in the part 1 of the box *B*, and these cells are filled or supplied accordingly. The paper *D* is then shifted so that its upper left-hand hole will be over the square marked *o*. This position of the paper exposes all the squares of the design marked 2, and indicates the different places of the colors in the part 2 of the box *B*. The paper *D* is then shifted so that its upper left-hand hole will be over the square *y* of the design, and the squares 3 will then be exposed, and the cells in the part 3 of the box *B* are filled with color accordingly. The paper *D* is then again shifted so that its upper left-hand hole will be over the square marked *z*, and the squares 4 of the design will be exposed, and the cells in the part 4 of the box *B* filled with color accordingly. From this description it will be seen that by charging the pins of the several blocks with color in their several compartments of the box *B*, and pressing the same on the cloth, the several blocks being used consecutively and so adjusted on the cloth that the pins of one block will be pressed between the impressions given or produced by the previous one, the whole surface of the cloth will be covered, and the design produced, as shown in Fig. 7. The whole process of printing is shown in Fig. 8, part 1 showing the impression given by the first block, the red circles indicating where the impression of the second block is given; part 2 showing the impressions of the first and second blocks combined; part 3 the impressions of the first, second, and third blocks combined, and part 4 the whole of the four blocks combined, the latter being the design shown in Fig. 7.

Another important feature of the invention is the manner in which the cells *c* are supplied with color. This is effected by means of plates *E E' E'' E'''*, having pins *d* inserted in them in positions corresponding to the several colors in the cells of the box *B*. The plate *E*, for instance, has its pins *d* corresponding to the positions of the cells *b*, which

contain the dark drab color. The plate *E'* has its pins corresponding in position to the cells of the light drab. The pins of plate *E''* correspond to the position of the ruby-cells, and the pins of the plate *E'''* correspond to the orange-cells. By dipping the pins of these several plates into pans or vessels *G*, containing the several colors, and then placing the pins in the cells, the latter will be supplied with color. This operation is gone through with from time to time, whenever the cells require replenishing.

I would remark that the employment or use of the cells *b* are not absolutely necessary. A pad or cushion, *H*, as shown in Fig. 5, might be used instead, the color being deposited by the plates or feeder *E E' E'' E'''* in separate or distinct spots on the pad or cushion, so that it can be taken up by the pins *a* of the blocks *A*. The cells, however, I deem preferable. The pins *d* may be secured in the plates *E E' E'' E'''* in any proper way; but they should be so attached as to be capable of being removed from the plates and adjusted therein in different positions, according to the design or pattern to be printed. Thus it will be seen that a design or pattern of any number of colors may be printed with four blocks only, thereby saving a great deal of labor in the printing process, and also avoiding the great expense attending the getting up of the old blocks.

I do not confine myself strictly to four blocks, for although not more than that number are required, a less number may in certain cases be advantageously used.

Having thus described my invention, what I claim as new, and desire to secure by Letters Patent, is—

1. The printing of designs or patterns on oil and other floor cloths, by means of blocks provided with pins or projections, arranged at such a distance apart and used in connection with a box containing cells supplied with different-colored paints, or with a pad or cushion supplied therewith, substantially as herein described.

2. The feeders or devices for supplying the cells or the pad or cushion *H* with the necessary colors, the same being composed of plates *E E' E'' E'''*, provided with pins *d*, substantially as set forth.

3. The perforated cam or paper *D*, as a means for disposing or distributing the pins *d* in the plates *E E' E'' E'''*, so as to supply the cells *b* of the box *B* or the pad or cushion with the several colors, that they may be taken up by the blocks to print the desired design or pattern.

JOHN MARCHBANK.
